US00D400354S

United States Patent [19]

[19]

[11] Patent Number: Des. 400,354

Burrows

[45] Date of Patent: **Nov. 3, 1998

[54] TRAY

D. 382,403 8/1997 Koskinen D3/307
3,170,594 2/1965 Nascher ..... D3/304 X

[75] Inventor: **Sharon Burrows**, London, England

FOREIGN PATENT DOCUMENTS

[73] Assignee: **Gratnell's Limited**, London, England

2136399 9/1984 United Kingdom ..... D3/304 X

[**] Term: 14 Years

Primary Examiner—M. N. Pandozzi

[21] Appl. No.: 61,248

frio

[22] Filed: Oct. 18, 1996

[57] **CLAIM**

[30] Foreign Application Priority Data

The ornamental design for a tray, as shown and described.

Apr. 18, 1996 [GB] United Kingdom 2055668
